UNITED STATES PATENT OFFICE.

NORMAL G. GORE, OF PLAINFIELD, NEW JERSEY, ASSIGNOR OF ONE-HALF TO JOSEPH N. MOORE, OF PLAINFIELD, NEW JERSEY.

HAIR-TRIMMER.

1,236,926.

Specification of Letters Patent. Patented Aug. 14, 1917.

Application filed January 8, 1917. Serial No. 141,284.

To all whom it may concern:

Be it known that I, NORMAL G. GORE, a citizen of the United States, residing at Plainfield, in the county of Union, State of New Jersey, have invented a new and useful Hair-Trimmer; and I do hereby declare the following to be a full, clear, and exact description of the invention, such as will enable others skilled in the art to which it 5 appertains to make and use the same.

The present invention relates to a safety hair trimming device, and has for its object to provide a device of this character which embodies novel features of construction 15 whereby a person can easily trim his own hair in a very satisfactory manner.

Further objects of the invention are to provide a device of this character which is comparatively simple and inexpensive in 20 its construction, which can be manipulated with perfect safety, which can be adjusted to trim the hair either short or long, and which will enable the most satisfactory results to be obtained without the assistance 25 of a professional barber.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in 35 which:—

Figure 1 is a side elevation of a hair trimmer constructed in accordance with the invention.

Fig. 2 is a horizontal sectional view on 40 the line 2—2 of Fig. 1.

Fig. 3 is a transverse sectional view on the line 3—3 of Fig. 1.

Fig. 4 is a detail perspective view of one end of the blade.

Fig. 5 is a similar view of the clamping bar.

Fig. 6 is a detail perspective view of the adjusting yoke and screw.

Fig. 7 is a transverse sectional view on 50 the line 7—7 of Fig. 1.

Corresponding and like parts are referred to in the following description and indicated in all the views of the drawings by the same reference characters.

55 Specifically describing the present em-

bodiment of the invention, the numeral 1 designates the back of the main frame, said back preferably having a tapered formation, and being provided at one end with a handle 2. A series of resilient guard 60 fingers 3 project from the back 1, said guard fingers having a spaced and parallel relation to each other and having the extremities thereof returned upon one side of the device, as indicated at 3^a. A guide arm 4 65 projects from the back 1 at each end of the series of guard fingers, and these guide arms are shown as provided upon the inner sides thereof with L-shaped slots 5 which open through their outer extremities. The cutting blade 6 extends transversely across the series of guard fingers 3 and is reversible, being provided at opposite sides thereof with cutting edges 6^a. The extremities of the blade 6 are received within the guide 75 grooves 5 of the arms 4 and terminate in lateral flanges 7 which interlock with the said grooves 5. The guard fingers 3 may be sprung to one side when inserting a blade 6 in position or removing it therefrom, although after the blade is properly positioned, the guard fingers are released, the returned ends 3^a thereof then extending around the outer cutting edge 6^a of the blade so as to prevent any object other than 80 a fine member such as a hair from coming into engagement with the cutting edge.

The blade 6 is provided at points toward opposite ends thereof with openings 8 which serve to detachably engage the hooked ends 90 9^a of an adjusting yoke 9. The middle of this yoke 9 has a swivel connection 10 with an adjusting screw 11 which is threaded in the back 1 and terminates in a finger piece 12. With this construction it will be obvious that by manipulating the finger piece 95 the blade 6 can be moved toward and away from the back 1 and adjusted to trim the hair either short or long.

The blade 6 is also provided at its longitudinal axis with a series of openings 13 for the reception of double headed pins 14, said pins projecting between certain of the guard fingers 3 and serving to engage a clamping bar 15 which serves both to reinforce and 100 stiffen the blade, and also to clamp the guard fingers against the blade so as to hold them securely in proper position. This clamping bar 15 is shown as provided with 105 key-hole slots 16 which are adapted to inter- 110

lock with the headed ends of the locking pins 14. When the bar 15 is moved longitudinally to bring the reduced ends of the key-hole slots 16 into engagement with the stems of the locking pins 14, the extremities of the locking bar spring into engagement with the guide arms 4 so as to coöperate therewith to hold the clamping bar in position. In order to remove the clamping bar 10 it is necessary to flex one end thereof outwardly and thereby disengage it from the guide arm 4 preparatory to sliding the bar longitudinally in the necessary manner to disengage the keyhole slots 16 from the 15 double headed locking pins 14.

In using the device it is drawn through the hair in much the same manner as a comb, being held at an inclination so that the outer cutting edge 6^a of the blade will engage the 20 ends of the hair. The guard fingers 3 prevent the cutting edge from engaging and injuring the scalp, and also operating in the same manner as the teeth of a comb to straighten the hair so that an even trimming 25 thereof is possible. If it is desired to trim the hair closely, the blade 6 is adjusted to bring the outer cutting edge 6^a thereof close to the outer ends of the guard fingers 3, while if it is merely desired to lightly trim 30 the hair, the cutting blade 6 is moved toward the back 1. It will be understood that the cutting blade is reversible so that both edges thereof can be used, and that when both edges have been dulled it can be readily replaced by a new cutting blade. When the 35 device is in use the guard fingers 3 are securely clamped between the bar 15 and the blade 6, and the bar 15 then engages the hooked ends 9^a of the adjusting yoke 9 in 40 such a manner as to prevent them from becoming disengaged from the openings 8 of the blade.

Having thus described the invention, what I claim as new and desire to secure by Letters Patent, is:—

1. A safety hair trimmer including a back, a series of guard fingers projecting from the back and terminating in returned ends, a guide arm at each end of the series of guard 50 fingers, a reversible cutting blade extending transversely across the guard fingers so as to be shielded by the returned ends thereof, the ends of the cutting blade having a slide- 55 able and interlocking connection with the guide arms, and means for adjusting the cutting blade.

2. A safety hair trimmer including a back, a series of guard fingers projecting from the back, a guide arm arranged at each end of 60 the series of guard fingers and provided with an L-shaped slot, a cutting blade extending transversely across the guard fingers and terminating at the ends thereof in flanges which slidably engage and interlock with the L-shaped slots of the guide arms, said cutting blade being also provided with openings, headed clamping pins projecting through the openings, and a clamping bar 65

arms, and means for adjusting the cutting blade.

3. A safety hair trimmer including a back, a series of guard fingers projecting from the back, a guide arm at each end of the series of guard fingers, a cutting blade extending transversely across the guard fingers and having the ends thereof slidably engaged by the guide arms, an adjusting yoke provided with hooked ends which detachably engage 75 the cutting blade, means engaging the adjusting yoke to slide the cutting blade in and out, and a clamping bar operatively connected to the cutting blade with the guard fingers clamped between the two 80 members, the clamping bar engaging the hooked ends of the adjusting yoke to retain the same in operative position.

4. A safety hair trimmer including a back, a series of guard fingers projecting from the 85 back, a guide arm at each end of the series of guard fingers, a cutting blade extending transversely across the guard fingers and having the ends thereof slidably engaged by the guide arms, means for adjusting the cutting blade, headed locking pins projecting from the cutting blade, and a clamping bar provided with key-hole slots for engagement with the headed locking pins, the extremities of the clamping bar engaging the 90 guide arms to lock the clamping bar in operative position.

5. A safety hair trimmer including a back, a series of guard fingers projecting from the back, a guide arm at each end of the series 100 of guard fingers, a cutting blade extending transversely across the guard fingers and having the ends thereof slidably engaged by the guide arms, an adjusting yoke terminating in hooked ends which detachably engage 105 the cutting blade, an adjusting screw engaging the yoke for coöperation therewith to move the cutting blade in and out, headed pins projecting from the cutting blade, and a clamping bar provided with key-hole slots 110 adapted to interlock with the headed pins, the ends of the clamping bar engaging the guide arms to hold the clamping bar in position, and the clamping bar engaging the hooked ends of the adjusting yoke to prevent 115 disengagement thereof from the cutting blade.

6. A safety hair trimmer including a back, a series of guard fingers projecting from the back, a guide arm arranged at each end of 120 the series of guard fingers and provided with an L-shaped slot, a reversible cutting blade extending transversely across the guard fingers and terminating at the ends thereof in outwardly projecting flanges 125 which slidably engage and interlock with the L-shaped slots of the guide arms, said cutting blade being also provided with openings, headed clamping pins projecting through the openings, and a clamping bar 130

formed with key-hole slots for engagement with the headed pins, the guard fingers being then clamped between the cutting blade and the clamping bar.

- 5 7. A safety hair trimmer including a back, a series of guard fingers projecting from the back, a guide arm arranged at each end of the series of guard fingers and formed with an L-shaped slot, a reversible cutting blade 10 extending across the guard fingers and terminating at its ends in outwardly projecting flanges which slidably engage and interlock with the L-shaped slots of the guide arms, said cutting blade being provided 15 with openings, an adjusting yoke engaging the cutting blade, means coöperating with

the adjusting yoke to move the cutting blade in and out, headed clamping pins projecting through the openings of the cutting blade, and a clamping bar provided with 20 key-hole slots for engagement with the headed pins, the guard fingers being then clamped between the cutting blade and the clamping bar.

In testimony whereof I have signed my 25 name to this specification in the presence of two subscribing witnesses.
